UNITED STATES PATENT OFFICE

170,568

STEREOSCOPIC CAMERA

John E. Davis, Sherman Oaks, Calif., assignor
to Revere Camera Company, Chicago, Ill., a
corporation of Delaware

Application July 28, 1952, Serial No. 20,783

Term of patent 14 years

(Cl. D61—1)

To all whom it may concern:

Be it known that I, John E. Davis, a citizen of the United States, residing at Sherman Oaks, State of California, have invented a new, original, and ornamental Design for a Stereoscopic Camera, of which the following is a specification, reference being had to the accompanying drawings, forming a part hereof.

Fig. 1 is a rear elevation of a stereoscopic camera showing my design;

Fig. 2 is an elevation of one side thereof;

Fig. 3 is an elevation of the other side thereof;

Fig. 4 is a front elevation thereof; and

Fig. 5 is an end view thereof, the opposite end being substantially identical thereto.

I claim:

The ornamental design for a stereoscopic camera, as shown.

JOHN E. DAVIS.
